ROBERT D. MADDOX, OF THE UNITED STATES ARMY.

ARTIFICIAL HAND.

1,280,262.

Specification of Letters Patent.

Patented Oct. 1, 1918.

Application filed July 25, 1918. Serial No. 246,732.

(DEDICATED TO THE PUBLIC.)

To all whom it may concern:

Be it known that I, ROBERT DANIEL MADDOX, Major, Medical Reserve Corps, United States Army, a citizen of the United States, 5 stationed at Washington, D. C., at the Army Medical School, have invented an Improvement in Artificial Hands, of which the following is a specification.

The invention described herein may be 10 used by the Government or any of its officers or employees in prosecution of work for the Government, or by any other person in the United States, without payment of any royalty thereon.

15 This invention generically relates to artificial body members; more specifically it comprehends an improved construction of mechanical hand, designed to firmly grasp various objects, and otherwise replace, in so far as possible, the manifold functions of the amputated member.

One object of this invention is to produce 20 an artificial hand of the simpler type, capable of rotary and angular adjustment depending upon the exigencies of the situation, and having facilities for securely grasping a working implement or other object between its gripping components. Another 25 object of this invention is to provide a cam actuated mechanism adapted to firmly secure the movable gripping member of the hand in any desired position in the path of its movement.

Other objects of this invention are to simplify 30 construction, decrease the cost of production, and otherwise improve the present forms of artificial hands.

With these and other objects in view, my 35 invention consists in certain novel constructions, combinations and arrangements of parts to be more particularly hereinafter set forth and claimed.

Briefly stated this invention comprises a 40 rotary and angularly adjustable shank, fixed claws at the free extremity of the shank, a longitudinally movable claw coöperating with the fixed claws, and means to firmly secure the movable claw at any desired point in the path of its movement.

45 Referring more particularly to the accompanying drawings, in which the corresponding parts are indicated by similar reference characters,

Figure 1 is a top plan view;

Fig. 2 is a longitudinal section on line 55 2-2 of Fig. 1;

Fig. 3 is a transverse section on line 3-3 of Fig. 2, in the direction of the arrows;

Fig. 4 is a front elevation of the wrist plate;

Fig. 5 is a fragmentary end elevation, illustrating the annular enlargement on the extremity of the same;

Fig. 6 is an end elevation of the shank with wrist plate removed.

In the illustrated embodiment characterized in this invention, there is shown a mechanical hand A, embracing a shank 10, furcated at its extremities, the furcations terminating in inwardly and downwardly 70 tapering gripping members, forming fixed claws 11', designed to coöperate with a movable claw 12, reversely curved and adjustably positioned on the shank 10. In order to permit longitudinal adjustment of the movable claw 12 with respect to fixed claws 11', said movable claw is secured to a carrier 13, comprising collars 14 and 14', slidably positioned on shank 10, and interconnected by a resilient bridge piece 15, as shown in Figs. 1 80 and 2 of the drawings. To fixedly secure the carrier 13 in any desired position on the shank 10, the collar 14' thereof is provided with a cam member 16 pivotally mounted as at 17. The pivoted extremity of lever 16 is 85 formed with a cam 18 adapted to engage the contiguous surface of collar 14, to which the upper end of the movable claw 12 is rigidly affixed. The other extremity of cam lever 16 is provided with a cam surface 19 de- 90 signed to engage the curved back of claw 12.

Obviously as the cam 18 is brought to operative position, collars 14 and 14' are divergently separated which causes their inner edges to bite in the surface of shank 10, 95 which retains the collar in its adjustable position. At the same time, cam surface 19 on the free extremity of the lever, coming into engagement with claw 12, coöperates with cam 18 to force claw 12 forward into 100 engagement with the object gripped. This forward movement of the claw brings the heel thereof into biting engagement with shank 10, to assist in firmly locking said claw in adjusted position. Furthermore the frictional engagement of surface 19 with the claw 12 serves as a lock to maintain the lever in operative position and prevents its 105

accidental displacement. To assist in its depression, lever 16 is formed with a thumb receiving recess 19'.

The foregoing construction concludes what 5 might be considered the gripping feature of this improved form of artificial hand.

Coming now to another important phase 10 of this invention, namely the means affording rotary as well as angular adjustment of the hand, upon referring to Fig. 2 of the drawing it will be seen this action is accomplished by providing a wrist plate 20, having an annular internally threaded flange 21. This arrangement forms a seat for the base 15 flange 22 of boss 23. Boss 23 is formed with a longitudinal passage 24 into which projects the enlargement 25 of shank 10. This enlargement is pivotally retained in position by pivot pin 26. A series of sockets 27 are 20 formed in the periphery of enlargement 25 to receive the stud 28 of lug 29 concentrically positioned on the wrist plate 21. The lug 29 is adapted to set in an annular recess 30 which communicates with the passage-way 24 of boss 23.

A winged nut 31 surrounding boss 23 is externally threaded as at 32 for engagement with flange 21, whereupon by simply screwing the nut 31 a clamping action is obtained 30 on the base of the boss, so that the latter may be rotated or fixedly retained as occasion may require. At the same time stud 28 being forced into socket 27, the shank 10 is maintained in its adjustable annular position.

If found to be advantageous, one of the fixed claws 11' may be formed with a small hook 38, having various uses. For example, after the extremity of the claw has been 40 passed through a button-hole, the hook may be caught at the edge of the button-hole and by a slight pull the garment containing the button-hole may be removed from the button. Also the hook might be used in opening or closing a purse, or in tying or untying a shoe string, or turning the leaves of a book and in many other useful ways.

Manifestly, from the preceding structure, to utilize this artificial hand for the purposes indicated, it is only necessary to release the wing nut, rotate the shank sufficiently to impart the desired rotary and angular adjustment to the claw, and then tighten the nut again to permanently hold 55 this adjustment. The object to be held is now positioned against the fixed claws, while the movable claw is advanced as far as possible. When this position has been obtained, the lever 16 is depressed, thereby forcing the 60 movable claw into firm and unyielding engagement with the object, so as to hold the same firmly and securely in position.

As a precautionary measure against accidental displacement of the gripping claws 65 after their rotary adjustment has been ob-

tained, the abutting surfaces of base flange 22 and wrist plate 20, are provided with an annular series of coacting tets and sockets 34 and 35, as clearly shown in Figs. 2, 4 and 6 of the drawings.

Although in the foregoing I have described certain elements as best adapted to perform the functions allotted to them, nevertheless it is to be understood that various minor changes as to form and the like may 70 be resorted to without departing from and sacrificing any of the benefits of this invention.

Having now described my invention, what I claim is:—

1. An artificial hand, comprising a pair of gripping members, one being longitudinally movable toward and from the other, means to secure the movable gripping member at any point in the path of its movement, and means to effect rotary adjustment of the gripping member.

2. An artificial hand, comprising a pair of gripping members, one being longitudinally movable toward and from the other, and means to effect their rotary and angular adjustment.

3. An artificial hand, comprising a pair of gripping members, one being longitudinally movable toward and from the other, means to secure the movable member at any point in the path of its movement and means to effect rotary and angular adjustment of said members.

4. An artificial hand, comprising a shank 100 terminating in a fixed gripping member, a gripping member longitudinally adjustable on the shank, and means for effecting the angular and rotary adjustment of said gripping members.

5. An artificial hand, comprising a plurality of fixed gripping claws, a movable claw adjustable toward and from the fixed claws, and means of effecting the rotary and angular adjustment of said claws.

6. An artificial hand, comprising a shank terminating in a plurality of fixed gripping claws, a movable claw longitudinally adjustable toward and from the fixed claws, and means to effect the rotary and angular adjustment of said claws.

7. An artificial hand, comprising a shank terminating in a plurality of fixed gripping claws, a carrier slidable on the shank, a gripping claw supported by the carrier and a 115 cam device to effect the frictional securement between carrier and shank.

8. An artificial hand, comprising a shank terminating in a fixed gripping claw, a carrier slidable on the shank, a gripping claw supported by the carrier, a cam device to effect frictional securement between the carrier and shank, and means to rotatably and angularly adjust said gripping members.

9. An artificial hand comprising a shank 130

terminating in a fixed gripping claw, a carrier slidable on the shank and embodying resiliently connected collars, a gripping claw supported by the carrier, and cam device 5 adapted to divergently separate said collars to effect frictional securement between the latter and said shank.

10. An artificial hand comprising a shank terminating in a fixed gripping claw, a carrier slidable on the shank and embodying resiliently connected collars, a gripping claw supported by one of said collars, a cam device secured to the other collar and adapted to divergently separate said collars to effect 15 frictional securement between the latter and said shank, and means to rotatably and angularly adjust said gripping members.

11. An artificial hand, comprising a shank portion, an element adjustably mounted on 20 the shank portion having a part adapted to frictionally engage said shank, and a canting device to effect securement between said adjustable element and the shank.

12. An artificial hand, comprising a shank portion, an element longitudinally positioned on the shank portion, and having a 25 resiliently connected part adapted to frictionally engage said shank, and a canting device carried by the adjustable element and operable to effect securement of the adjustable element on the shank.

13. In an artificial hand, the combination with the shank having a fixed claw at one end and an annular enlargement, at the other, of a movable claw slidably mounted 35 on the shank and operable toward and from the fixed claw, a rotatable anchoring member pivotally connecting the enlarged end of said shank, clamping means to engage said anchoring member, and additional means to 40 inter-lockingly engage the enlarged end of said shank.

14. An artificial hand, comprising a pair of gripping members, one being longitudinally adjustable toward and from the other, 45 and means for effecting their rotary adjustment, substantially as described.

15. An artificial hand, comprising a pair of gripping members, one being longitudinally adjustable toward and from the other, 50 and means for effecting their angular adjustment, substantially as described.

16. An artificial hand, comprising a pair of gripping members, one being longitudinally movable toward and from the other, 55 means to secure the movable gripping member at any point in the path of its movement, and means for effecting the angular adjustment of the gripping member, substantially as described.

ROBERT D. MADDOX.
